Primary Examiner—Gary D. Watson**Attorney, Agent, or Firm**—Learman & McCulloch**[57] CLAIM**

The ornamental design for a folding chair with three legs, as shown and described.

DESCRIPTION

FIG. 1 is a front elevational view;
FIG. 2 is a side elevational view, the view from the opposite side being identical;
FIG. 3 is a rear elevational view;
FIG. 4 is a top plan view; and,
FIG. 5 is a bottom plan view.

The schematic mesh-like depiction of fabric on the seat and backrest is understood to be continuous throughout the intended surface.
